RE-ENTRY BODY

Clarence B. Cohen, Redondo Beach, Warren G. Koerner, Manhattan Beach, and Irvin N. Spielberg, Pacific Palisades, Los Angeles, Calif., assignors to Thompson Ramo Wooldridge Inc., Redondo Beach, Calif., a corporation of Ohio

Filed Jan. 2, 1964, Ser. No. 77,997

Term of patent 14 years

(Cl. D71—1)

Fig. 1.

Fig. 2.

Fig. 4.

Fig. 3.

Fig. 5.

FIGURE 1 is a top plan view of a re-entry body showing our new design with the broken line showing omitted for convenience of illustration;

FIGURE 2 is a side elevation view thereof;

FIGURE 3 is a rear elevation view thereof;

FIGURE 4 is a front elevation view thereof; and

FIGURE 5 is a perspective view thereof.

The dominant features of our design reside in the portions shown in full lines.

We claim:

The ornamental design for a re-entry body, substantially as shown and described.
